Primary Examiner — Richard E Chilcot(74) *Attorney, Agent, or Firm* — Lawrence Cruz, Esq.; Ryan, Mason & Lewis, LLP(57) **CLAIM**

The ornamental design(s) for a multiple configuration lock, as shown and described.

DESCRIPTION

FIG. 1 is a perspective view of the multiple configuration lock in accordance with the principles of the present disclosure depicted securing a single loop shackle in phantom; FIG. 2 is a right side elevation view of the multipl configuration lock;

FIG. 3 is a top plan view of the multiple configuration lock; FIG. 4 is a front axial view of the multiple configuration lock;

FIG. 5 is a bottom plan view of the multiple configuration lock;

FIG. 6 is a rear axial view of the multiple configuration lock; FIG. 7 is a left side elevation view of the multiple configuration lock; and,

FIG. 8 is a perspective view of the multiple configuration lock depicted securing a double loop shackle in phantom. Any portions of the figures shown in broken lines are for illustrative purposes only and for no part of the claimed design.
